UNITED STATES PATENT OFFICE.

ALVIN ALLEN, OF NORTH BROOKFIELD, MASSACHUSETTS.

TOOL FOR CHANNELING SOLES.

Specification forming part of Letters Patent No. 42,546, dated May 3, 1864.

To all whom it may concern:

Be it known that I, ALVIN ALLEN, of North Brookfield, in the county of Worcester and State of Massachusetts, have invented an Improved Device for Channeling Soles; and I do hereby declare that the following, taken in connection with the drawings which accompany and form part of this specification, is a description of my invention sufficient to enable those skilled in the art to practice it.

In channeling soles or cutting a groove around and near the edges thereof for the reception of the stitches or seam by which the soles are secured to the vamps on a sewing-machine it has been customary to first cut with a straight edged knife an incision around and parallel to the edge of the sole, and to the depth to which the channel is to be made, and then to run a tubular knife or plow through the bottom of this incision to form the channel. Each of these operations was distinct; and my invention consists in cutting both the incision or groove and the channel at the bottom thereof at one manipulation by combining the two knives in one holder or stock.

My invention is illustrated in the accompanying drawings, in which Figures 1 and 2 represent, respectively, front and side views of a holder with the two knives applied thereto. Figs. 3, 4, 5, and 6 represent a modification of the invention, the knives being there shown, respectively, in front, side, and edge views and in section. Figs. 7 and 8 denote the form of the channel.

In carrying out my invention, as seen in Figs. 3, 4, 5, and 6, the straight-edge knife *a* is formed on the bottom and as a part of the shank *b*, and the tubular knife *c* extends from the knife *a*, as shown. The knife *a* is set angular with respect to the shank *b*, and so that in operating the instrument the groove from the surface of the sole to the channel is cut diagonally or on a slant from said surface, as shown in Fig. 7. This forms a flap, *d*, above the channel *e*, which, upon being rubbed up and back, as seen in Fig. 8, leaves the channel open to the top of the sole and the sole

ready for application to the vamp to which it is to be secured, the channel, after receiving the stitches, being again covered by the flap *d*, so as to conceal and protect the stitches.

In the instrument shown, Figs. 1 and 2, instead of uniting in one piece of metal the straight and tubular knives *f g*, I make the knives separately and fasten their shanks in a stock or holder, *h*, by a plate, *i*, or in any other suitable manner, the groover being set so as to run just in advance of the tubular knife or plow *g*, and so that the groove shall run from the surface of the sole to the channel. By this arrangement the knives can be adjusted with respect to each other and can be at any time separately removed and sharpened when it may be necessary.

The instrument shown in Figs. 3, 4, 5, and 6 is applied to a holder in a similar manner to that shown with the two knives *f g*. The bottom surface, *l*, of this holder regulates the depth of cut of the knives, they being set at such distance out from said surface as it is desirable to form the channel. Lips or guides *k* extend down from the surface *l* on one side of the knives, said lips being kept against the edge of the sole in using the knives and keeping the channel and groove parallel to or equidistant from said edge.

What I claim is—

1. The employment of a channeling-knife and grooving-knife applied to a stock, to operate together substantially in the manner and for the purpose specified.

2. So applying the knives to the stock or holder that they can be adjusted with respect to each other or separately removed for repairs or other purpose, as set forth.

3. Constructing the stock or holder with the surface *l* and lips or guides *h*, whereby the depth of cut of the channel and its distance from the edge of the sole is gaged, as set forth.

ALVIN ALLEN.
